US0D1094277S

(12) **United States Design Patent** (10) **Patent No.:** **US D1,094,277 S**
(45) **Date of Patent:** **** Sep. 23, 2025**

(54) **CHARGER**

(71) Applicant: **Jianwei Liu**, Shenzhen (CN)

(72) Inventor: **Jianwei Liu**, Shenzhen (CN)

(**) Term: **15 Years**

(21) Appl. No.: **29/944,795**

(22) Filed: **May 30, 2024**

(51) **LOC (15) Cl.** **13-02**

(52) **U.S. Cl.**

USPC **D13/107**

CLAIM

The ornamental design for a charger as shown and described.

DESCRIPTION

FIG. 1 is a perspective view of a charger showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an enlarged view of portion 10 shown in FIG. 2. The dash-dash broken lines in the drawings depict portions of the charger that form no part of the claimed design. The dot-dash broken lines represent boundaries of the enlarged portion and form no part of the claimed design.

1 Claim, 10 Drawing Sheets
